(57) **CLAIM**

The ornamental design for a hand sleeve for a clutch bag, as shown and described.

DESCRIPTION

FIG. 1 is a front perspective view of a first embodiment of a hand sleeve for a clutch bag;

FIG. 2 is a front view thereof;

FIG. 3 is a first side view thereof;

FIG. 4 is a second side view thereof;

FIG. 5 is a top view thereof;

FIG. 6 is a bottom view thereof;

FIG. 7 is a front perspective view of a hand inserted within the hand sleeve;

FIG. 8 is a front perspective view of a second embodiment of a hand sleeve for a clutch bag;

FIG. 9 is a front view thereof;

FIG. 10 is a first side view thereof;

FIG. 11 is a second side view thereof;

FIG. 12 is a top view thereof;

FIG. 13 is a bottom view thereof; and,

FIG. 14 is a front perspective view of a hand inserted within the hand sleeve.

The evenly spaced broken lines showing a handbag, portions of the sleeve and a hand are for the purposes of illustrating environment. The dot-dashed broken lines represent the boundaries of the claimed design. Neither broken lines form part of the claimed design.
